UNITED STATES PATENT OFFICE.

ROBERT JACKSON, OF HOMER, LOUISIANA.

DIKE.

1,248,660.

Specification of Letters Patent.

Patented Dec. 4, 1917.

Application filed June 6, 1914. Serial No. 842,408.

To all whom it may concern:

Be it known that I, ROBERT JACKSON, a citizen of the United States, and a resident of Homer, in the county of Claiborne and

5 State of Louisiana, have invented certain new and useful Improvements in Dikes, of which the following is a specification, reference being had to the accompanying drawings, forming a part of this specification.

10 The invention has for its object to guard against the submergence of low-lands, as for instance, in reclaiming such lands, particularly of a fertile character.

15 A further object is to carry out the aforesaid ends in an economical, simple and effective manner and with facility.

20 The invention therefore consists of certain structural features, including the combination and arrangement of parts substantially as hereinafter fully disclosed and defined by the appended claim.

25 In the accompanying drawings is illustrated the embodiment of my invention wherein it will be understood that various changes and modifications as to the detailed construction and arrangement of parts may be made without departing from the spirit of the invention, and in which drawing:

30 Figure 1 is a side elevation of my invention as applied for the diking off a low-land.

Fig. 2 is a transverse section thereof taken through the gate.

35 Fig. 3 is also a like section upon an enlarged scale, taken at a point disclosing more especially the concrete base at the bottom of the dike.

Fig. 4 is an opposite or inside elevational view of my dike, and

40 Fig. 5 is a plan view thereof, both these latter views also showing the practical application of my invention.

45 In carrying out the aim of my invention, I suitably erect the dike or barrier, designated generally as 1, transversely of the stream's bed and include a galvanized sheet metal plate or sheathing 2, after the fashion of a roof-sheathing. Said sheet metal or sheathing 2 is suitably secured or nailed to suitable horizontal members or stringers 3, 50 in turn fastened or nailed to posts 4, suitably anchored in the ground, as clearly seen in Figs. 1 and 2 and braced as at 4^a. In the

ground at the base of the structure, as thus erected, is suitably laid in an excavation, a layer of concrete 5, forming a sub-base, this 55 sub-base of concrete being designed primarily to guard against the overflowing water getting down under the dike. Within the sub-base of concrete 5 are suitably horizontally embedded wooden blocks 6 having one 60 end exposed to which is nailed as at 7, or otherwise fastened, the lower edge of the sheet metal sheathing 2.

A suitable sliding gate or closure 8 is provided for the opening and shutting of an 65 opening 8^a in the dike 1, to allow the passage of just enough water through the dike to relieve or guard against overflow. The laterally sliding closure or gate 8 is received and guided at its upper end below an offset guide 70 member 9 secured to the sheet 2; the bottom edge of said closure or gate is let into, and guided within a longitudinal groove 10 formed in the concrete sub-base 5, supporting the closure. 75

From the foregoing it will be observed that the water is effectively controlled.

A dike embracing the general features of my invention may be adapted to be positioned laterally, or at the side of the stream. 80

I claim—

In a dike of the character described, a sub-base formed of concrete, a plurality of horizontally disposed wooden blocks embedded within said base having one end exposed, a 85 metal plate having a centrally disposed square opening secured to said blocks, an offset guide member secured to said plate above said opening a groove being formed within said base below said guide member, a gate 90 slidably held by said guide member and groove whereby said gate may be actuated to expose said opening, a plurality of horizontally disposed stringers secured to said plate, a plurality of posts embedded adjacent to 95 said base secured to said stringers, and a brace bar secured to each of said posts, all arranged as shown.

In testimony whereof I affix my signature, in the presence of two witnesses.

ROBERT JACKSON.
